HAND GRENADE

Earl Douglass Hibbs, Philadelphia, Pa.

Application March 22, 1941, Serial No. 384,735

2. Claims. (Cl. 102—64)

This invention relates to improvements in hand grenades and more particularly to hand grenades which are adapted to be released for discharge by the action of centrifugal force imparted to the grenade when thrown.

The use of explosive hand grenades is, of course, very old. In the conventional hand grenade, ignition or detonation is usually accomplished by a percussion cap or primer. A locking pin or the like is usually employed which, when withdrawn, sets the grenade for ignition of a primer.

A good many difficulties have existed in connection with hand grenades of the prior art. Due to the inherent danger of the hand grenade once it is released for firing, the thrower promptly throws the hand grenade into the region of the enemy. However, many instances have been recorded where, after removing the safety pin and before throwing the grenade, the thrower has been wounded or killed and the live grenade has discharged in the midst of the thrower's own comrades. Additionally, the handling in transportation of hand grenades has been highly precarious and dangerous.

It is an object of the present invention, first, to devise a hand grenade which will be so proportioned and formed as to meet the natural aptitude of the average soldier. In this connection, the hand grenade of the present invention is made in precisely the shape and size of a standard baseball; in the throwing of which practically every soldier is proficient.

Second, it is an object of the present invention to provide a hand grenade in such form that the firing mechanism may be transported separately from the casing and main explosive charge and need only be assembled in the field adjacent the point of use. In this way the hazards incident to transportation are practically completely eliminated.

Third, it is an object of the invention to provide a hand grenade which may be cheaply produced largely from die castings and pressings which can be manufactured and assembled without expensive machining operations.

Further and more detailed objects, purposes, and advantages of the invention will become apparent as the description thereof proceeds.

Referring to the drawings:

Figure 1 is a side elevation of a completely assembled hand grenade viewed from the side through which the firing mechanism is mounted;

Figure 2 is a cross-sectional view in the direction of the arrows along line 2—2 of Figure 1;

Figure 3 is a detailed perspective view of the sealing plug for the firing mechanism;

Figure 4 is a detailed perspective view of one form of locking pin bearing plate employed in the firing mechanism;

Figure 5 is a detailed perspective view of the fuse carrying casting suitably employed in the firing mechanism;

Figure 6 is a further detailed view of a spacing ring employed in the firing mechanism;

Figure 7 is a detailed view of the safety pin;

Figure 8 is an exploded view showing the manner of assembling the firing mechanism in the precharged grenade casing;

Figure 9 is a cross-sectional view similar to Figure 2 but showing a modified form of firing mechanism;

Figure 10 is a perspective view of the sealing plug employed in the modification of Figure 9; and

Figure 11 is a detailed perspective view of the modified form of locking pin bearing plate employed in the structure of Figure 9.

Referring to Figure 1, the cast iron casing of the hand grenade is indicated generally by the reference character 1 and is preferably, although not necessarily, grooved as indicated at 2 to insure that it will break up into small fragments when exploded. The casing 1 is provided with a comparatively small screw-threaded opening 3 designed to receive the closing plug 4. The purpose of the opening 3 is to permit introduction of a molten explosive which is cast about a core on the inside of the casting 1 as indicated generally at 5.

The firing mechanism is indicated generally by the reference character 6, and its relationship to the casing 1 and cast explosive 5 is particularly well shown in Figure 8. The casing 1 has a comparatively large screw-threaded opening 7, through which the entire firing mechanism 6 is adapted to be passed, and a sealing plug 8 screwed into the casing through the means of a suitable wrench fitting in the recesses 9 to bring the firing mechanism 6 into fully assembled position.

Referring to Figure 8, the core which is used in casting the explosive 5 in the casing 1 suitably takes a form precisely corresponding to the form of the casing enclosing the firing mechanism 6. After the explosive 5 is cast in the casing 1 about the core, the core may be removed, and the casing containing the cast explosive is then ready to be transported to the scene of action. It will be observed that the interior wall

of the casing 1 opposite the opening 7 is slightly recessed, as indicated at 10, to receive and seat the end of the detonator 11.

Coming to a description of the firing mechanism, it will be observed that the outer casing 12 thereof has its larger end fitted over the inner end of the sealing plug 8 with a rolled joint as indicated at 13. The smaller end of the casing 12 has an opening 14 through which the detonator 11 extends. The open end of the explosion cap is flanged, as indicated at 15, and seats against the inner wall of the smaller end of the casing 12. The detonator 11 contains a detonating charge of quick burning powder or other suitable primer which upon ignition ruptures the detonator 11, thus setting off the main explosive charge 5, which may be T. N. T. or other suitable explosive.

Fitted into the casing 12 next to the open end of the detonator 11 is the fuse and percussion cap carrying casting 16, shown in detail in Figure 5. This casting is provided with a fuse carrying channel 17 which extends outwardly from a rupturable percussion cap 18 and communicates through an opening 19 with a similar fuse channel 20 which leads directly to the explosive charge in the detonator 11. A centrally apertured disk 21 is seated immediately in advance of the fuse carrying casting 16. A spacing sleeve 22 abuts the disk 21. A second substantially larger centrally apertured disk 23 is mounted immediately in advance of the spacing sleeve 22 with the central aperture 24 thereof affording a bearing for the inner end of the firing pin 25. Immediately in front of the disk 23 is positioned a second spacing ring 26, shown in detail in Figure 6, which is provided at one side with a locking pin receiving opening 27 and at its opposite side with a keyway 28. The locking pin bearing disk 29 is press-fitted into the sleeve 26 with one arm 30 thereof in alignment with the opening 27 in the sleeve 26 and another arm 31 thereof in alignment with the keyway 28 in the sleeve 26.

Struck out from the disk 29 are two inner bearing arms 32 and 33. The arms 31 and 32 are suitably apertured to receive the locking pin 34 while the arms 30 and 33 are apertured to receive the locking pin 35. The disk 29 also has a central aperture 36 through which the firing pin 25 extends. The locking pin 34 has rigidly connected therewith a weight 37, and locking pin 35 carries a corresponding weight 38. These weights 37 and 38 are normally urged inwardly by the action of springs 39 and 40 seated, respectively, between the weight 37 and arm 31 and the weight 38 and arm 30, the action being such that the inner ends of the locking pins 34 and 35 extend into the transverse bore 41, which extends through the firing pin 25, and hold the same against any inward movement induced by the action of the spring 42.

The sealing plug 8 is fitted into the other end of the casing 12 and abuts the spacing ring 26. It completely seals the firing unit 6 of the grenade and has an opening therethrough, indicated at 43, to receive the partially split frictionally held safety pin 44 carrying the ring 45. The opening 43 in the sealing plug 8 is adapted to be positioned in direct alignment with the keyway 28 in the sleeve 26 whereby the safety pin 44, when it is in the position shown in Figure 2, effectively locks the locking pin 34 against outward movement and prevents unintentional release of the firing pin 25.

Now describing the operation of the hand

grenade, when the casing 1 with its cast charge 5 and the firing mechanism 6, as shown in Figure 8, are separately received in the field, they are suitably assembled by inserting the firing mechanism through the opening 7 in the casing 1 and screwing the plug 8 home which brings the end of the detonator 11 into the recess 10.

The thrower of the grenade then takes the hand grenade in his normal throwing hand, with the sealing plug 8 containing the safety pin 44 positioned within the circle formed by the thumb and index finger, and then grasps the ring 45 of the safety pin 44 with his other hand and withdraws the same. The hand grenade is then thrown in precisely the manner that a baseball is thrown. The resulting centrifugal force causes the weights 37 and 38 to move radially outwardly, carrying with them the locking pins 34 and 35. The outer end of the locking pin 35 passes into the opening 27 in the sleeve 26, and the outer end of the locking pin 34 passes into the keyway 28 of the same sleeve. This results in a release of the firing pin 25, which, under the action of the compression spring 42, is forced through the central aperture of the disk 21 into the rupturable percussion cap 18, setting it off and igniting the fuse disposed in the communicating channel 17, 19, and 20. This channel is of such length and proportions as to give a predetermined short time interval between the time of release of the firing pin 25 and the explosion of the detonator 11 to thereby permit the hand grenade to arrive at its contemplated destination, at which point the rupture of the detonator 11 sets off the main explosive charge, resulting in the disintegration of the casing 1 with explosive effect.

Referring to the modification shown in Figures 9 to 11, it will be observed that in this construction the disk 46 carrying the locking pin bearings is made to serve the purpose of the disk 23, sleeve 26, and plate 29 of the embodiment disclosed in Figures 1 to 8. This is achieved by forming the disk 46 with a diameter equal to the internal diameter of the larger portion of the casing 12, so that the disk 46 may seat directly against the spacing ring 22, and by otherwise specially constructing the disk 46 as hereinafter explained.

It will be observed that, in addition to carrying locking pin bearing arms 30, 31, 32, and 33, the disk 46 is provided with somewhat longer diametrically opposed legs 47 and 48. The free ends of these legs are designed to be received in and held by the notches 49 and 50 of the modified sealing plug 51 shown in Figure 10. It will be noted that the notches 49 and 50 are each ninety degrees removed from the keyway 52 in the plug 51. Thus, when the legs 47 and 48 of disk 46 are assembled with their free ends in notches 49 and 50 of sealing plug 51, the keyway 52 will register with the outer surface of one of the bearing arms 30 or 31 in such manner that when the safety pin 44 is pressed into position, its free end will lie between one of the bearing arms 30 and 31 and the inner wall of the casing 12 to thereby effectively lock either the locking pin 34 or the locking pin 35 against radial movement, thus precluding unintentional release of the firing pin 25. In all other respects the modification of Figures 9 to 11 compares with the embodiment of Figures 1 to 8.

The modification of Figures 9 to 11 has certain advantages by way of simplification of construction and reduction in cost of manufacture

and assembly. It will be observed that all of the elements entering into the hand grenade may be easily manufactured by well-known methods. The outer casing 1 is of cast metal. The only machining operations necessary comprise the threading of the openings 3 and 7. The plug 4 may be a die-cast suitably-threaded plug. The sealing plug 8 and the fuse carrying casting 16 may likewise be produced by merely conventional die-casting methods. The casing 12, various disks, spacing rings, and bearing plates of the firing mechanism 6 are readily producible by die-pressing and forming and may be easily assembled by relatively unskilled persons.

From the foregoing, it will be observed that the hand grenade of the present invention is highly effective, safe, extremely economical to produce, and especially advantageous from the standpoint of assembly and ability to separately transport the firing mechanism and the main explosive charge.

Having thus described my invention, I claim:

1. A hand grenade comprising, in combination, a precharged casing containing explosive molded to receive a firing mechanism and a separable firing assembly adapted to be inserted through an opening in a wall of said casing and to fit into the molded explosive therein, said firing mechanism embracing a metal casing carrying a precharged detonator at one end thereof, a preformed time fuse carrying member in juxtaposition to the charge of said detonator, a percussion cap associated with said member, a firing pin operable to strike said percussion cap to ignite said fuse, a centrally apertured disk sur-

rounding said firing pin, diametrically opposed bearing arms on said disk, radially disposed locking pins carried by said bearing arms, spring means urging said locking pins into contact with said firing pin to hold said firing pin against movement, and weights on each of said locking pins responsive to centrifugal force upon throwing of the grenade to force said locking pins radially outward against said spring means to release said firing pin.

2. A hand grenade comprising a spherical casing containing a cast explosive charge having a recess therein, a firing assembly adapted to be inserted into said recess through an opening in said casing, said firing assembly comprising a detonator at the inner end of said recess, a time fuse and a percussion cap associated with said detonator, a spring actuated firing pin operable to strike said percussion cap, a centrally apertured disk surrounding said firing pin and overlying said percussion cap, a pair of radially spaced bearing arms extending upwardly from said disk, a locking pin carried by said bearing arms, resilient means urging said locking pin into contact with said firing pin to maintain said firing pin spaced from said percussion cap, a weight carried by said locking pin responsive to centrifugal force to move said locking pin radially outward in opposition to said resilient means to release said firing pin, and a removable safety pin in contact with the outer end of said locking pin to positively prevent outward movement of said locking pin prior to removal of said safety pin.

EARL DOUGLASS HIBBS.
